EXTENSION LADDER BRACKET

Kalman A. Sliuvak, Cleveland, Ohio

Application September 22, 1951; Serial No. 247,823

2. Claims. (Cl. 228-25)

1.

This invention relates generally to the ladder art and is particularly concerned with an extension ladder which can be quickly and easily assembled and disassembled and with a new fitting for use with an extension ladder to facilitate such assembly and disassembly.

Heretofore extension ladders have been assembled and disassembled by being slid endwise relative to one another. The lower ladder, i. e., the one which rests on the ground, carries fixed L-shaped brackets which extend upwardly from the side rails thereof and overhang the side rails of the upper ladder and retain the ladders in assembled position. Such an extension ladder can be erected against a building and taken down only with the expenditure of considerable effort because the ladders must be assembled before being raised or erected against the building. The need has long existed for an extension ladder which could be quickly erected or taken down with little effort and with which the assembly or disassembly may be accomplished while the lower ladder is standing in erected position against the building. So far as I know, this demand has never been supplied prior to my invention.

These objects are attained by the present invention in which fittings are attached to one side rail of the lower ladder which may be locked in position to hold the upper ladder assembled with the lower ladder or in position to permit relative sidewise movement of the ladders in assembling or disassembling the ladders.

The present invention will be better understood by those skilled in the art from the following specification read in conjunction with the accompanying drawings, in which:

Fig. 1 is a fragmentary view of an extension ladder embodying the present invention and equipped with fittings embodying that invention, these fittings being shown in different adjusted positions;

Fig. 2 is a fragmentary, cross-sectional view taken on line 2-2 of Fig. 1 through one of the fittings and showing in dotted line an adjusted position of the fitting; and

Fig. 3 is a cross-sectional view taken on line 3-3 of Fig. 1.

In Fig. 1 the extension ladder comprises a lower ladder having side rails 1 and rungs 2 and an upper ladder having side rails 3 and rungs 4.

One side rail of the lower ladder is equipped with two rigid brackets 5 of the conventional type in which flanges extend laterally at the outer or upper ends to overlie one side rail 3 of the upper ladder. The opposite side rail 1 of the lower ladder is equipped with adjustable fittings.

Each of these adjustable fittings comprises a lower plate 10 having a lateral, outwardly extending end 11 and a bifurcated end having eye portions 12 provided with aligned pivot-receiving apertures, one aperture 13 being non-cylindrical, preferably rectangular in cross-section. The aperture 14 in the other eye portion is preferably cylindrical in cross-section. The fitting also includes an upper plate 15 having an inward laterally extending upper end portion 16 and an eye 17 at its other end receivable between eye portions 12 of plate 10 and provided with an aperture 18 which is non-cylindrical and preferably rectangular in cross-section but conforming to the cross-section of aperture 13. The fitting also includes a pin 20 having a non-circular, preferably rectangular portion 21 adjacent to its head conforming to and of a size to enter apertures 13 and 18 and prevent relative rotation of plates 10 and 15. At the opposite end of the pin 20 a cotter pin 22 retains in compression a spring 23 which is coiled around pin 20 and bears at one end against the cotter pin and at the other end against the lower plate 10.

As will be seen by referring to Figs. 1 and 3, the lower plates 10 of the adjustable fittings are secured against the inner face of one side rail 1 of the lower ladder opposite to the fixed brackets 5, bolts 25 serving to hold the rail and plate in assembled position with end portion 11 projecting underneath the side rail. When the pins 20 are moved endwise upwardly, as in Figs. 1 and 3, against the compression of spring 23, the non-circular portions 21 may be moved up out of apertures 18 in upper plate 15 whereupon that plate may be turned through approximately 90° to the position shown in dotted lines in Fig. 2 and in full lines in the lower fitting of Fig. 1. With both fittings adjusted in this manner the upper ladder may be assembled with the lower ladder by being moved sidewise relative to the lower ladder to bring one side rail under fixed brackets 5 and the other side rail within the inner side of the opposite rail 1 of the lower ladder, i. e., the two ladders are thus brought into assembled position. Then, by again moving the pins to bring the portions 21 out of apertures 18, the upper plates 15 of each fitting may be moved to the full line position in Fig. 2, i. e., the position shown by the upper fitting of Fig. 1, where the lateral end portions 16 of the fittings will overlie the adjacent side rail of the upper ladder and hold the ladders in assembled position and the portions 21 of the pins will enter apertures 18 when the pins are allowed to move endwise in response to the springs 23 thereby locking plates 10

and 15 against rotation. The ladders may be readily disassembled by reversing the foregoing procedure, i. e., moving pins 20 endwise against springs 23 until portions 21 move out of apertures 18 and then rotating the upper plates 15 to clear the side rail of the upper ladder. Thus the plates 15 may be locked in each position and all danger of accidental disassembly in use is avoided.

When the apertures 13 and 18 are rectangular in cross-section, plate 15 may be locked in positions 90° apart and suitable for retaining the ladders in assembled position and permitting assembly and disassembly. Apertures of more or less than four sides may be used instead of the four-sided apertures 13 and 18 if desired, the important factors being the locking of the plate 15 in the specified positions.

Since the upper ladder may be assembled and disassembled with the lower ladder by moving the upper ladder sidewise, the assembly and disassembly may be made while the lower ladder is in erected position and this work may be accomplished by a single individual since he can readily handle one ladder and move it sidewise whereas, due to the weight and awkwardness of two ladders, two men are often required to erect an extension ladder.

Having thus described the present invention so that others skilled in the art may be able to understand and practice the same, I state that what I desire to secure by Letters Patent is defined in what is claimed.

What is claimed is:

1. In an extension ladder including a lower ladder having side rails an upper ladder having side rails disposed between and adjacent to the side rails of the lower ladder and rigid brackets attached to one side of the lower ladder and projecting over the upper edge of the adjacent side rail of the upper ladder, the combination of adjustable means for retaining the two ladders in assembled relation and permitting assembly and disassembly thereof by moving the upper ladder laterally relative to the lower ladder, said adjustable means comprising two similar fittings spaced apart longitudinally of the ladder and opposed to the said rigid brackets, each of said adjustable fittings comprising a lower flat plate secured against the inner side of the adjacent side rail of the lower ladder, an upper angle shaped plate to lie close to the outer side and top edge of the adjacent side rail of the upper ladder and to rotate about 90° away from said side rail, said plates having pivot-receiving eye portions positioned approximately midway between the upper and lower edges of the adjacent side rail of said upper ladder, one of said plates having two spaced apart eye portions provided, respectively, with cylindrical and non-cylindrical pivot-pin-receiving holes and the other plate having an eye portion between the said two eye portions and

provided with a pivot-pin-receiving hole conforming in cross-section to that of the said non-cylindrical hole of the other plate, a pivot pin having a head at its upper end and a shank in and conforming in cross-section to the cross-sections of said holes in said eye portions, and spring means on the lower end of said shank and compressed against the adjacent plate for urging said pin downwardly endwise to bring its non-cylindrical parts into said non-cylindrical holes of the plates thereby to lock the upper plate in position to retain the upper ladder in assembled position relative to said lower ladder.

2. A fitting for retaining the upper and lower ladders of an extension ladder in assembled relation and for permitting assembly and disassembly thereof by moving the upper ladder laterally relative to the lower ladder, comprising a lower flat plate to be secured against the inner side of the adjacent side rail of the lower ladder, an upper, right angle shaped plate to lie close to the outer side and top edge of the adjacent side rail of the upper ladder, said plates having pivot-receiving eye portions to be positioned approximately midway between the upper and lower edges of the adjacent side rail of said upper ladder, one of said plates having two spaced apart eye portions provided, respectively, with cylindrical and non-cylindrical pivot-pin-receiving holes and the other plate having an eye portion between the said two eye portions and provided with a pivot-pin-receiving hole conforming in cross-section to that of the said non-cylindrical hole of the other plate, a pivot pin having a head at its upper end and a shank in and having axially spaced sections conforming in cross-section to the cross-sections of said holes in said eye portions, and spring means on the lower end of said shank and compressed against the adjacent plate for urging said pin downwardly endwise to bring its non-cylindrical parts into said non-cylindrical holes of the plates thereby to lock the upper plate in position to retain the upper ladder in assembled position relative to said lower ladder, said spring permitting upward endwise movement of said pin in the opposite direction to bring its non-cylindrical part into only one of said eye portions and thereby to permit the angle plate to be rotated through about 90° to clear the adjacent side rail of the upper ladder.
